DISPLAY STAND

Michael Emhoff, 1480 Ocean Ave., Brooklyn, N.Y.

Filed Jan. 14, 1966, Ser. No. 1,274

Term of patent 14 years

(Cl. D80—9)

FIG.1

FIG. 1 is a top plan view of a display stand, showing my new design;

FIG. 2 is a front elevational view thereof; and

FIG. 3 is an elevational view taken from one side thereof.

This is a continuation-in-part of design application Serial No. D.83,662, filed February 2, 1965, now abandoned.

I claim:

The ornamental design for a display stand, as shown and described.
